UNITED STATES PATENT OFFICE.

MICHAEL NEIL AND FRANK H. BISSELL, OF DAYTON, OHIO.

WIRE FENCE.

SPECIFICATION forming part of Letters Patent No. 601,272, dated March 29, 1898.

Application filed July 29, 1897. Serial No. 646,314. (No model.)

To all whom it may concern:

Be it known that we, MICHAEL NEIL and FRANK H. BISSELL, citizens of the United States, residing at Dayton, in the county of 5 Montgomery and State of Ohio, have invented certain new and useful Improvements in Wire Fences, of which the following is a specification.

Our invention has relation, in a wire fence, 10 to posts having removable slanting slotted or slotted brace rods or bars with removable in- cased wire-stretching devices and adjustable anchoring or tension straining devices detachably connected with said slanting brace rods or bars, and in such connection it relates particularly to the general construction and arrangement of the said several members of the fence.

The principal objects of our invention are, 20 first, to provide a simple, durable, ornamental, and comparatively inexpensive post and concealable means for stretching taut the line wires or runners and relieving the slanting rods or bars from direct strain of the stretched wires; second, to provide a wire fence with 25 an efficient concealable wire-stretching device; third, to provide a wire fence with corner or end posts each having a fluted spire-shaped cap or head with a removable perforated collar having an elbow for engaging 30 therewith a slanting brace bar or rod adapted to contain a wire-stretching device or devices and an adjustable tension and anchoring appliance for relieving the direct strain of the 35 line wires or runners upon said slanting brace or rod and end or corner posts and embrac- ing each corner or end post anchored in the ground or secured into a suitable foundation, and, fourth, to provide a wire fence with posts 40 and wire-stretching devices and anchoring means which are readily separable as well as adapted to be quickly assembled, and, fur- 45 ther, in which the direct strain on the brace bars or rods sustaining the wire-stretching devices in a concealed condition as well as the end or corner posts is compensated for by the adjustable anchoring means embrac- 50 ing the said posts and adjustably connected with said brace rods or bars of the fence.

55 Our invention, stated in general terms, consists of the improvements in a wire fence con-

structed and arranged in substantially the manner hereinafter described and claimed.

The nature and scope or characteristic features of our invention will be more fully understood from the following description, taken in connection with the accompanying drawings, forming part hereof, in which—

Figure 1 is a side elevational view of a section of a fence with the several elements embodying our invention illustrated in operative condition in the same. Fig. 2 is a top or plan view of Fig. 1. Fig. 3 is a view, partly in section and partly in elevation, of a portion of a corner or other post with its accessories and a portion of the slanting brace rod or bar detachably applied thereto and adapted to contain and conceal a wire-stretching device or devices. Fig. 4 is a perspective view of the coupling device of the post with its elbow 60 for attaching the slanting brace rod or bar thereto of Figs. 1 and 2. Fig. 5 is a view, partly in elevation and partly in section, of the corner or other post with its connections with a slanting brace rod or bar and the wire- 65 stretching device concealed therein embodying particular features of our invention. Fig. 6 is a perspective view of one of the adjustable wire-stretching devices of our invention removed from its housing in the slanting brace 70 rod or bar. Fig. 7 is a vertical central sec- 75 tional view through the device of Fig. 6. Fig. 8 is a lower end view of the device of Figs. 6 and 7. Fig. 9 is a perspective view of the locking or gravity pawl of the wire-stretch- 80 ing device detached therefrom; and Fig. 10 is a perspective view of a chamfered or ribbed 85 surface wedge for use in the slanting brace rod or bar, in conjunction with each of the wire-stretching devices of Fig. 6, for securing 90 the said device firmly in required position in said bar or rod.

Referring to the drawings, A represents an end or corner hollow metal post provided with a removable fluted spire-shape cap or head a. Beneath this applied cap or head a to the hollow post A is suitably mounted and secured a perforated collar a', having formed integral with or secured to the same a recessed elbow a'', as clearly illustrated in Figs. 3 and 5. To 95 this elbow is detachably secured a slotted or slotted hollow slanting brace rod or bar, B,

resting at the bottom upon a foundation *b* or fitted directly into the ground.

- C* is an adjustable tension anchoring or strain compensating appliance comprising two bars *c* and *c'*, one of which, *c*, is formed into a ring *c²* at one end and embraces the slanting brace rod or bar *B* and at the other end terminates in an eye *c³*. The other rod or bar, *c'*, is suitably fastened at one end in the slanting brace rod or bar *B* and at the other end in an eye *c⁴*, connected with the eye *c³* of the rod or bar *c* and with a ring *c⁵*, embracing the post *A*. This ring is in movable engagement with a rod *c⁶*, provided with an anchoring-plate *c⁷*, adapted to be secured into the ground or in a suitable foundation *A'*. The respective rods or bars *c* and *c'* are preferably parted at or about the middle of the same and threaded to receive sleeve-nuts or turnbuckles *c⁸* and *c⁹*, whereby any slackening of the said rods *c* and *c'* may be taken up as well as strain upon the slanting brace-rod *B* and post *A* compensated for by the device *C*, hereinabove fully explained.
- D* is a wire-stretching device comprising a casting of substantially circular form and ribbed externally on one side or surface at *d* and on the opposite side or surface recessed or offset at *d'* and *d²* and provided with a lug *d³*, and in front provided with an overlapping or curved flange *d⁴*, adapted to enter the slit or slot of said brace rod or bar *B*, so as to contour with the same, and thereby when the device *D* is mounted or slid to place in the said slanting brace rod or bar *B* to prevent turning or wabbling thereof.
- d⁵* is a slotted reel mounted in and journaled to the two depending members *d⁶* and *d⁷* of the casting *D* and carrying a toothed wheel *d⁸* for turning said reel *d⁵*, which on the outer end beyond the wall of the depending member *d⁶* of the casting *D* is provided with a pawl-locking or tooth wheel *d⁹*, engaged by a detachable gravity-pawl *d¹⁰*, provided with a pin *d¹¹*, movable up and down in a slot *d¹²*, which is provided in the member *d⁶* of the casting *D*, for example, of the type illustrated in Figs. 6 and 9 of the drawings.
- d¹³* in Fig. 10 is an arched and ribbed wedge adapted to be inserted between the inner wall of the slanting bar *B* and the device *D*, as illustrated in application in Fig. 8, to thereby securely hold the said device to place in said slanting bar or rod *B*.
- Each wire or runner *E* of the fence is adapted to be wound upon the slotted reel *d⁵* of a device *D*, mounted on the brace rod or bar *B*, by operating by means of a wrench or other suitable appliance the toothed or ratchet wheel *d⁸*, and during the turning of the said reel the toothed or ratchet wheel *d⁹* will be

permitted to turn by lifting the gravity-pawl *d¹⁰* out of engagement in sequence with the teeth of said wheel. When the actuation of the winding ratchet or toothed wheel *d⁸* of the reel *d⁵* has been stopped, said gravity-pawl will fall into a space between two teeth of said wheel *d⁹* and thereby hold the same against unwinding or slip of the said reel *d⁵*.

It will be manifestly obvious that as to minor details certain modifications may be made, and particularly as to the wire-stretching device, without departing from the spirit or scope of our invention, and hence we do not wish to be understood as limiting ourselves to the precise construction and arrangement of all the elements as illustrated and as hereinbefore explained; but,

Having thus described the nature and objects of our invention, what we claim as new, and desire to secure by Letters Patent, is—

1. The combination, in a wire fence, of a post provided with a slanting slotted or slit-brace rod or bar, a wire-stretching device, substantially as described, mounted in said bar or rod and adapted to be wedged to position therein, and an adjustable tension or anchoring appliance connected with said bar or rod, embracing said post and secured in a suitable foundation, substantially as and for the purposes described.

2. The combination, in a wire fence, of a post provided with a slanting slotted or slit-brace rod or bar, a wire-stretching device provided with a reel actuated by a toothed wheel and said reel having a locking toothed wheel engaged by a gravity-pawl, said device adapted to be wedged to position in a concealed condition against movement in said slanting brace rod or bar, substantially as and for the purposes described.

3. The combination, in a wire fence, of a post provided with a detachable slanting slotted brace-rod having a wire-stretching device mounted in the same and adapted to be wedged against movement, said device having ratchet-actuating means and gravity-pawl-locking means for preventing slip of the stretched wire and an adjustable tension or anchoring appliance for relieving direct strain upon said slanting brace-rod and post of said stretched wires, substantially as and for the purposes described.

In testimony whereof we have hereunto set our signatures in the presence of two subscribing witnesses.

MICHAEL NEIL.
FRANK H. BISSELL.
